B. E. TAYLOR.

CAN CHARGING APPARATUS.

APPLICATION FILED JAN. 10, 1921.

1,393,406.

Patented Oct. 11, 1921.

Inventor
Bert C. Taylor.

By his Attorney

UNITED STATES PATENT OFFICE.

BURT E. TAYLOR, OF MOUNT VERNON, NEW YORK, ASSIGNOR TO THE BORDEN COMPANY, OF NEW YORK, N. Y., A CORPORATION OF NEW JERSEY.

CAN-CHARGING APPARATUS.

1,393,406.

Specification of Letters Patent. Patented Oct. 11, 1921.

Original application filed December 13, 1919, Serial No. 344,713. Divided and this application filed January 10, 1921. Serial No. 436,063.

To all whom it may concern:

Be it known that I, BURT E. TAYLOR, a citizen of the United States, and a resident of Mount Vernon, county of Westchester, 5 and State of New York, have invented certain new and useful Improvements in Can-Charging Apparatus, of which the following is a specification, this being a division of my application Serial Number 344,713, 10 filed December 13, 1919, on which has been granted Letters Patent No. 1,373,275, dated March 29th, 1921, for can-charging apparatus.

My present invention relates to apparatus 15 in aid of charging, or filling, cans, particularly those of the well-known cylindrical, sheet-metal, type employed for example as containers of evaporated milk, or other liquid, or liquefied, *i. e.* flowing materials 20 so susceptible to infection from exposure to the atmosphere, that their container cans have to be hermetically sealed and to that end charged through relatively small openings in the top as per present approved and well-understood practice.

The objects of my present invention comprise provision of novel means, and appliances, whereby the said materials are automatically chargeable into the cans with more 30 speed, less wastage, less disturbance and less exposure to atmospheric or other injury than heretofore.

These objects I attain by aid of my invention comprising the novel adjuncts and mechanical factors, elements and parts, examples of which and of their operation are illustrated in the accompanying drawings, in which—

Figure 1 is a partly sectional and partly 40 side elevational view illustrative of my invention;

Figs. 2 and 3 are, on enlarged scale, transverse views principally in central vertical section taken on the line 2—2 of Fig. 1, and 45 illustrative of the relations to each other of certain of the parts shown in Fig. 1 at different stages of their operation; and

Fig. 4 is, on enlarged scale, a central sectional view of the top of a can and its opening.

I provide for the material, a cylindrical receptacle 19 of capacity such as to hold somewhat more of the material than required to fill the can 20 through an opening

20' in the head 20" (Fig. 4). It will be 55 understood that the can is, in this instance, of the usual sheet-metal variety and air tight, except for its said opening.

The receptacle has adjacent its bottom 60 downwardly extended delivery outlet 19'. The top of the receptacle is closed, or open, as may be preferred, and the material fed into it in any convenient manner.

The receptacle comprises a detachable tip 21, through which passes the outlet 19' as 65 shown in the drawings. This tip is composed of rigid material, preferably of hardened metal and comprises, for a purpose hereafter described, a part, or face-plate, having a substantially plane downwardly 70 presented surface 21' extending annularly, and radially outwardly, from and completely surrounding said outlet, and has also a downwardly extending tubular flange portion 21" having an angular edge, 21", concentric with, and closely surrounding the path of the outlet 19'. The inner surface 75 of the flange constitutes a part of the inner surface of the outlet (see Figs. 2 and 3).

Underneath the outlet 19' I provide a 80 movable, *i. e.* vertically reciprocable, can support, 29, (Fig. 1), which comprises a leg 29' slidably mounted in a stationary part of the frame F. A pin 29", carried by the leg, is held slidably in a slot 32' located in 85 one arm of a rock lever 32, pivoted as at 32" to the frame.

The lever is positively rocked and held by aid of a link 46 carried by the other arm of the lever. The link carries a roller (not 90 shown) which cooperates with an internal cam 47, rotated by the shaft 30, and shaped and timed to impart the requisite reciprocations and intervening pauses to the can support. I provide, within the receptacle, a reciprocable punch-bearing valve member, 48, having an operative projection, 48', which is passable through the outlet 19' into the can, and preferably so snugly fits the outlet as to close it to the flowing material. This 100 punch is reciprocated by aid of a link, or rod 49, slidably supported in guides 50, 50', carried by the frame, and carrying a roller 51, coacting with a cam 52, carried by the shaft.

I provide the following means to exhaust air from the can, *viz.* an oscillatory spindle valve 53, normally closing the outlet 19' and

adjustably rotatable therein by aid of a thereby carried arm 54, carrying a roller 54', with which co-operates a rotary cam 55, carried by the shaft 30, and provided with a 5 projection 55', and shaped and timed to cause the valve to temporarily assume, and to maintain while required, the position shown in Fig. 3. The normal position of this valve is that shown in Fig. 2, and it is returned 10 thereto and held therein by a retractile spring 56, connecting the arm 54 with the frame F. The valve 53, is rotatably mounted in a stationary cylindrical shell or seat 57, carried by the frame F to which it is 15 joined by the union 57'. An expansile spring 58, bears against the union and the valve to keep the latter properly seated. The valve 53, comprises a stem 53' containing, as does the valve, a concentric bore, or 20 air duct 53'', which is connected by aid of a rubber hose 59, or other unrigid connection, with any preferred air-exhausting apparatus (not shown).

The valve 53, contains a by-pass for the 25 material, *i. e.* an eccentric transverse bore 59, which communicates with the outlet 19' when the valve is in its normal position shown in Fig. 2.

The valve also contains a radial bore, or 30 channel 60, communicating with, its concentric bore, or air duct, 53'' and which also communicates with a lateral enlargement, 19''', of the outlet 19', when the valve has been oscillated by the cam 55 to the position 35 shown in Fig. 3.

Operation: The valve and the punch being in the positions shown in Fig. 2, and the can suitably positioned on the then depressed support 29, so that the opening, or top, of 40 the can is concentric with the outlet 19', a single rotation of the shaft 30, serves to force the can up against the tip 21, thereby causing the punch 48, to puncture the head, or to enlarge a previously made opening there-in. This results in distorting the sheet-metal and producing an air-tight joint between it and the receptacle 19, as will be apparent and is also more fully described in my said Patent No. 1,373,275. The punch 50 is then raised sufficiently for it to clear the valve 53, whereupon the latter is turned into the position shown in Fig. 3 and air exhausted from the can through the valve. The punch-bearing member is then completely withdrawn from the outlet 19', as 55 indicated in Fig. 1, and the valve is then returned to its position shown in Fig. 2, thereby causing the by-pass to communicate with the receptacle and with the can through the 60 outlet, and the material is permitted to flow by gravity and atmospheric pressure from the receptacle into the exhausted can. The flow is stopped by again lowering the punch into the outlet 19' as shown in Fig. 3, and the 65 valve 53 is oscillated back to its normal

position closing said outlet. The filled can is then lowered and removed and the cycle indefinitely repeated.

It will be understood that, in usual practice, the heads of the cans contain a relatively small central opening, or aperture, of usually not to exceed one thirty-second of an inch in diameter, such opening being illustrated in Fig. 4. But such opening is, although preferable, not essential, the operative end 48', of my punch-bearing member 48 being competent to puncture the head, as well as to enlarge such opening,—the cross sectional diameter of the punch in this instance being say about one-sixteenth of an 80 inch.

The construction and operation are such as to result in the proper exhausting and charging of a can by a comparatively unskilled operator and through a relatively 85 minute opening more expeditiously, economically, hygienically than heretofore.

Having now described my invention, what I claim as new and desire to secure by Letters Patent is the following, viz:

1. In apparatus for charging a flowing material into a container, a receptacle for the material having adjacent its bottom a downwardly delivering outlet; a reciprocable valve member within said receptacle 90 co-operating with said outlet; an oscillatory valve below said receptacle also co-operating with said outlet, and containing an air-duct and also a by-pass for the material, and means to oscillate said last mentioned valve 100 and thereby bring said air-duct and said by-pass alternatively into communication with said outlet.

2. In apparatus for charging a flowing material into a container, a receptacle for the material having adjacent its bottom a downwardly delivering outlet; within said receptacle a movable valve member co-operable with said opening to close it; and a spindle valve disposed and oscillatable transversely of said outlet and containing an air-duct and also a by-pass for the material, said by-pass and air-duct being alternately communicable with said outlet according to the oscillation of said spindle valve.

3. In apparatus for charging a flowing material into a can, a receptacle for the material having adjacent its bottom a downwardly extended delivery outlet; a valve in said outlet movable therein and containing a by-pass for the material and an air-duct; a punch bearing member reciprocable within said outlet, said by-pass, and said can; means to turn the valve so that the by-pass communicates with the receptacle and the can, and alternately so that the air-duct communicates with the can through a part of said outlet; and means to reciprocate the punch-bearing member while the by-pass and outlet are in communication.

4. In apparatus for charging a flowing material into a can, a receptacle for the material having adjacent its bottom a downwardly extended delivery outlet; a spindle valve disposed transversely of and rotatable in said outlet and containing a by-pass for the material and an air-duct; a punch-bearing member reciprocable within said outlet, said by-pass, and said can; said by-pass and 10 air-duct being alternately communicable with said can through said outlet according to the position into which said spindle valve is rotated; and means to reciprocate the punch-bearing member while the by-pass and outlet are in communication.

5. In apparatus for charging a flowing material into a can, a receptacle for the material having adjacent its bottom a downwardly extended outlet; a spindle valve disposed and oscillatable transversely of said outlet and containing an air-duct and also a by-pass for the material, said by-pass and air-duct being alternately communicable with said outlet according to the oscillation of said spindle valve; and a punch-bearing member advanceable from said receptacle into the can when said outlet and by-pass are in communication. 20 25

BURT E. TAYLOR.
